CLAIM

I claim the ornamental design for an eyeglass stick pin, as shown and described.

DESCRIPTION

FIG. 1 is a front elevation of my new design of an eyeglass stick pin;

FIG. 2 is a rear elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken line showing of beads and end cap are included for the purpose of illustrating environmental structure and forms no part of the claimed design.
